UNITED STATES PATENT OFFICE.

AARON W. H. WARSCHAVSKY, OF BROOKLYN, NEW YORK.

WAVE-MOTOR.

1,379,145.

Specification of Letters Patent. Patented May 24, 1921.

Application filed December 13, 1918, Serial No. 266,546. Renewed August 14, 1920. Serial No. 403,510.

To all whom it may concern:

Be it known that I, AARON W. H. WARSCHAVSKY, a citizen of the United States of America, and a resident of the borough of Brooklyn, in the city of New York, county of Kings, and State of New York, have invented certain new and useful Improvements in Wave-Motors, of which the following is a specification.

10 The present invention relates generally to wave motors and its main feature resides in means for utilizing the fall as well as the rise of waves. Another feature of the invention is the arrangement of the parts 15 in units of such character that any number of units may be grouped for actuation of a power translating device, such as a generator. A still further feature of the invention resides in the fact that a floating structure is used, on which all the mechanism is 20 mounted, together with means for adjusting said structure with respect to the surface of the water.

The invention is embodied in a concrete 25 and preferred form in the accompanying drawings, in which—

Figure 1 is a top plan view of a single unit showing one exemplification of the invention.

30 Fig. 2 is a view in elevation, with parts broken away, of the unit shown in Fig. 1.

Fig. 3 is a detail view, partly in section, of the floating and rotatable members of the unit shown in Figs. 1 and 2.

35 Fig. 4 is a fragmentary sectional view on the line 4—4 of Fig. 3.

Fig. 5 is a detail view partly in section of a modified form of the invention shown in Fig. 3.

40 Fig. 6 is a view, in elevation, of a group of units arranged to actuate a single power translating device.

Considering first the invention as disclosed in Figs. 1 to 4, 1 indicates a floating 45 structure constructed of steel beams and braces as indicated. This floating structure is carried by a number of tanks or pontoons 2 and is rendered unresponsive to wave motion by suitable flexible connections 3 that 50 are anchored at the bottom of the ocean or lake, the structure being immersed to a considerable depth and below the action of the waves and below the point of buoyancy of the structure. The cables 3 are wound 55 on sheaves 4 mounted on shafts 5 geared together by shaft 6 and bevel gears 7. By

these means, all of the cables may be wound or unwound in unison, a motor 8 and a reduction gear 9 being conveniently used to effect rotation of shaft 6. Suitable means, 60 such as ratchets and pawls (not shown), may be used to prevent unwinding of the cables.

10 indicates a floating member free to rise and fall in response to the motion of waves. 65 In this instance, this member consists of a small tank 11 that forms a buoyant member and slides 12 that engage in guides 13 of the frame work of the device. It will be understood that wave motion will cause the 70 floating member 10 to reciprocate in its guides, the amplitude of this reciprocating motion depending upon the action of the waves. The means for utilizing both the up and down stroke of this floating member 75 take, in this instance, the following form. 14 and 15 indicate two transmission members here consisting of sheaves around which are passed cables 16, the free ends of which are attached at the upper and lower ends 80 of member 10. Said members 14 and 15 are idly mounted for rotation on driver shafts 17 and 18, a ball clutch 19 being interposed between transmission member 14 and shaft 17 and another ball clutch 20 be- 85

ing interposed between transmission member 15 and shaft 18. The two clutches 19 and 20 are arranged to act in opposite directions with respect to each other so that, when member 10 rises, both of the transmission members 14 and 15 are rotated and shaft 18 is turned in the direction indicated by the arrow, shaft 17, however, remaining stationary. On the down stroke of member 10, both transmission members 14 and 15 are 90 again rotated but in the opposite direction and shaft 17 is now turned in the direction indicated by the arrow, while shaft 18 re- 95 mains stationary. It will be observed that shafts 17 and 18 turn in the same direction 100 but that they are operated on different strokes of reciprocating member 10. Shafts 17 and 18 are connected to a suitable power translating device such as generator 21. This connection is, in this instance, effected 105 by means of pulleys 22 and 23 on shafts 17 and 18, belts 24 and 25, pulleys 26 and 27, main shaft 28, pulleys 29 and 30 and belt 31.

In Fig. 5 is shown an alternate form in 110 which the reciprocating member 10 is in the form of a double-faced rack 10^a meshing

with transmission gears 14^a and 15^a which latter are connected by means of clutches 19 and 20 to shafts 17 and 18, the arrangement of the clutch being the same as that shown in Fig. 3. It will be understood that by the means described both the up and down stroke of the floating member may be utilized for the production of power and that by providing a great many units the accumulation of power may be made very considerable. In Fig. 6 is shown, in diagrammatic form, how a number of such units may be combined. It will, of course, be understood that shafts 17 and 18 may be of considerable length and that any number of clutches, transmission members and floating members may be used in connection with said shafts; and that the irregular action of a number of reciprocating floating members, due to difference in wave, height and length, will in nowise cause interference but that said shafts will simply accumulate all the power supplied by any of the devices connected therewith. Similarly, a number of units may be grouped one behind the other in the manner indicated in Fig. 6. In this form of the invention, shafts 17 and 18 of the same unit are connected by means of pulleys 32 and belts 33; and shafts 18 and 17 of adjacent units are connected by means of pulleys 34 and 35 and belt 36. The power produced by the units may then be taken off any one or more of the shafts and preferably as shown in Fig. 6. Pulleys 37 and 38 may constitute the means in connection with belts 39 and 40 whereby power will be transmitted to shaft 41 of power translating device 21. Any one of the floating members, if it is desired to render it inoperative, may be raised and held on a support 42.

I claim:

1. A wave motor comprising: a supporting structure including pairs of spaced horizontally disposed beams, guides in vertical alinement carried by said beams, a vertically reciprocating floating member responsive to wave motion, slide members secured thereto and extending upwardly through said guides, a power translating device, and means for utilizing the action of the floating member to actuate the power translating device.

2. A wave motor comprising: a supporting structure including pairs of spaced horizontally disposed beams, guides in vertical alinement carried by said beams, a vertically reciprocating floating member responsive to wave motion including: a buoyant member, an elongated beam secured thereto, and slide members secured to said beam and extending upwardly through said guides, a power translating device, and means for utilizing the action of the floating member to actuate the power translating device.

3. A wave motor comprising: a floating

structure unresponsive to wave motion including a plurality of horizontally disposed beams arranged in pairs, the beams of each pair being in spaced relation, the pairs of beams being in superposed relation, guides in vertical alinement carried by said beams, a vertically reciprocating floating member responsive to wave motion, slide members secured to said floating member and extending through said guides, a power translating device on the floating structure and means for utilizing the action of the floating member to actuate the power translating device also on the floating structure.

4. A wave motor comprising: a floating structure unresponsive to wave motion including a plurality of horizontally disposed beams arranged in pairs, the beams of each pair being in spaced relation, the pairs of beams being in superposed relation, guides in vertical alinement carried by said beams, a vertically reciprocating floating member responsive to wave motion, slide members secured to said floating member and extending through said guides, two rotatable transmission members between the superposed beams and guides, rotated by the reciprocating member during both its up and down stroke, two rotatable power members rotatable in the same direction, two clutches, one between each transmission and power member and acting in opposite directions to thereby rotate one power member during the up stroke of the reciprocating member and to rotate the other power member in the same direction as the first power member during the down stroke of the reciprocating member, and means connecting the two power members.

5. A wave motor comprising: a floating structure including pairs of spaced horizontally disposed beams, guides in vertical alinement carried by said beams, a plurality of flexible means for anchoring said structure to make it unresponsive to wave motion, a vertically reciprocating floating member responsive to wave motion, slide members secured thereto and extending upwardly through said guides, a power translating device on the floating structure, means for utilizing the action of the floating member to actuate the power translating device also on the floating structure and means for simultaneously shortening or lengthening the flexible connections including: a plurality of shafts, drums on said shafts on which the flexible connections are adapted to be wound, a shaft connecting the plurality of shafts and means for rotating said shaft.

6. A wave motor comprising: a floating structure unresponsive to wave motion; a plurality of shafts on said floating structure, drums mounted on said shafts, flexible connections wound on said drums and adapted to be anchored to the bottom of the ocean

or lake, a shaft connected to said shafts by gears, and means for rotating said shaft to simultaneously shorten or lengthen the flexible connections, a floating member responsive to wave motion, a power translating device on the floating structure and means for utilizing the action of the floating member

to actuate the power translating device also on the floating structure.

Signed at the borough of Manhattan, in the city, county and State of New York, this 9th day of December, 1918.

AARON W. H. WARSCHAVSKY.
